UNITED STATES PATENT OFFICE

172,445

SLEIGH

Frederic N. Seaver, Long Island City, N. Y.

Application September 10, 1953, Serial No. 26,762

Term of patent 14 years

(Cl. D14—34)

To all whom it may concern:

Be it known that I, Frederic N. Seaver, a citizen of the United States of America and a resident of Long Island City, in the county of Queens, State of New York, have invented a new, original, and ornamental Design for a Sleigh, of which the following is a specification, reference being had to the accompanying drawing, forming a part hereof.

Fig. 1 is a side elevational view of a sleigh embodying my invention.

Fig. 2 is a front elevational view thereof on a reduced scale.

Fig. 3 is a similar rear elevation, and

Fig. 4 is a perspective view thereof also on a reduced scale.

I claim:

The ornamental design for a sleigh, substantially as shown.
